Primary Examiner — Michael C Stout*Assistant Examiner* — Fitzgerald L Butac*(74) Attorney, Agent, or Firm* — Kathleen Chapman(57) **CLAIM**

The ornamental design for a gear, as shown and described.

DESCRIPTION

FIG. 1 is a front, top, right side perspective view of a gear, showing our new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.
